Attorney.

UNITED STATES PATENT OFFICE.

SAMUEL D. MORRIS, OF MOUNT AUBURN, INDIANA.

RAIL-TONGS.

1,246,142.

Specification of Letters Patent. Patented Nov. 13, 1917.

Application filed February 15, 1917. Serial No. 148,794.

To all whom it may concern:

Be it known that I, SAMUEL D. MORRIS, a citizen of the United States, residing at Mount Auburn, in the county of Wayne and 5 State of Indiana, have invented new and useful Improvements in Rail-Tongs, of which the following is a full, clear, and comprehensive specification and exposition, the same being such as will enable others to 10 make and use the same with exactitude.

The object of my invention, broadly speaking, is to provide a tool for handling railway-rails, structural steel, and other material for which the tool is or may be adapt- 15 ed, the same being strong and durable in construction, substantially automatic in operation, easily operated and controlled, comparatively light in weight, and which can be manufactured and sold at a compara- 20 tively low price.

More specifically stated, the object is to provide a tool adapted to be suspended by a cable or the like, which latter may operate over a pulley carried by a swinging-arm, 25 derrick, crane, or a jib, in the usual manner, the said tool being provided with jaws adapted to automatically engage around the head of a rail or the like, and having means whereby the jaws may be released by a per- 30 son located at a distance therefrom, that is by the person who controls the operations of the cable and the crane or the like.

Other objects and advantages will suggest themselves in the course of the following description, and that which is new will be correlated in the appended claims.

The preferred means for carrying out my invention in a practical manner is shown in the accompanying drawings, in which—

40 Figure 1 is a side elevation of my invention in operative position and in connection with a railway rail. Fig. 2 is a central longitudinal vertical section of the device. Fig. 3 is a front side elevation of the device. 45 Fig. 4 is a perspective view of the major jaw alone. Fig. 5 is a perspective view of the minor jaw alone. Fig. 6 is a cross section, as taken on the line 6—6 of Fig. 7. And Fig. 7 is a rear side elevation, showing the 50 addition of a clevis which is pivoted to the body portion.

Similar indices denote like parts throughout the several views.

In order that the construction, the operation, and the advantages of my invention 55 may be more clearly understood and appre-

ciated I will now take up a detailed description thereof in which I will set forth the invention as fully and as comprehensively as I may.

Referring now to the drawings in detail: Numeral 1 denotes the flat tubular body, which is rectangular in cross section; and extending slightly outward and then directly downward from the two narrow sides 60 or edges thereof are the identical arms 2 and 3, the lower ends of which are connected by the relatively stationary cross-pin 4, whose purpose will hereinafter appear.

Fitting slidably in the hollow or slot 70 formed by the interior of the body 1 is the stem 5 which projects through and some distance above the body 1 and also a short distance therebelow, substantially as indicated in the drawings.

Formed integral with the lower end of the stem 5 is the triangular head 6, with its apex merging with the stem 5, and its outer lower corners having the downwardly directed flanges 7 and 8, which project below the base 80 9 of the head; and the lower ends of said flanges are rounded, substantially as shown.

Cutting the flange 7 into three equal parts are the slots *a* and *b*; and likewise cutting the flange 8 into three equal parts are the slots *c* and *d*, which are for the purpose 85 hereinafter appearing.

Formed horizontally and centrally through the flange 7 is a round aperture which receives the pivot pin 10 which, manifestly, passes across through the slots *a* and *b*. And likewise formed horizontally and centrally through the flange 8 is a round aperture which receives the pivot pin 11 which, manifestly, passes across through the slots *c* and 90 *d*, substantially as indicated.

The jaws 12 and 13 are identical with each other, the only difference being that the major jaw 12 has two inwardly directed lugs 14 and 15, while the minor jaw 13 has but one inwardly projecting lug, which is denoted by the numeral 16.

Formed through each of the lugs 14, 15 and 16 is a curved slot, 17, 18 and 19, respectively, which slots are in alinement with each other, and they are parallel with each other when the jaws are in closed position, as in Fig. 1.

Formed opposite to the lugs 14 and 15, and also integral with the jaw 12, are the ears 20 and 21, which have alined apertures therethrough to receive the pin 11 and which

fit in the slots *c* and *d*. Likewise formed opposite to the lug 16, and also formed integral with the jaw 13, are the ears 22 and 23, which have alined apertures there-through to receive the pin 10, and they fit in the slots *a* and *b*. From the above it will be noticed that the jaws are hinged to the head 6, each by a knuckle joint.

When the jaws are assembled it will be seen that the jaw 12 will be pivoted on the pin 11, and the jaw 13 will be pivoted on the pin 10. Also that the lug 16 will be located between the lugs 14 and 15, and with the pin 4 located in the slots 17, 18 and 19.

When the jaws are closed, as in Fig. 1, the lugs 14, 15 and 16 will contact with the underface of the head 6, that is with the base 9 of the head, and when opened they will stand as in Fig. 2.

Extending out from the face side of the body 1 is a bracket having the spaced sides 24 and 25, and at its upper end is the outwardly extending finger 26 having a vertical aperture through the outer portion thereof.

Between the sides 24 and 25 the body is cut away forming an opening into the interior of the body.

Pivoted on the pintle 27 is the dog 28, whose nose is adapted to contact with the stem 5, and to engage in the notches *x*, *y* or *z*.

An outwardly extending ear 29 is formed integral with the dog.

Numeral 30 denotes a rod which is disposed through the alined apertures in the ear 29 and the finger 27, the same having a head 31 on the lower end thereof to contact with the ear 29, and an eyelet 32 is formed on its upper end. The upper portion of the rod 30, below the eyelet 32, is threaded to receive the nut 33 which is adapted to contact with the finger 26.

Numeral 34 denotes a helical spring which surrounds the rod 30 and it contacts with the finger 26 and with the ear 29, and it is adapted to normally retain the nose of the dog in the notches *x*, *y* or *z*, or to cause it to contact with the face of the stem 5.

Formed in the upper end of the stem 5 is an aperture *w* which is to receive the ring 34, in which latter may be secured one end of the cable 35. Secured in the eyelet 32 is the line 36 by which the dog may be released. Letter A denotes a railwav rail.

An aperture *s* is formed through the rear face of the body 1, as shown in Fig. 7, primarily this aperture is formed when the aperture for the dog 28 is formed through the opposite side of the body, but incidentally it serves as an oiling aperture.

In some instances I provide a clevis 37, whose ends approach near the edges of the upper portion of the body 1, from which latter protrude pivots 38 and 39 which extend through the eyes of the clevis, and the clevis is thereby secured on said pivots, and

it is retained thereon by the cotter-pins 40 and 41.

In practice the device is suspended by the cable 35, the weight of the jaws and of the lugs 14, 15 and 16 causing the jaws to normally stand in open position, as in Fig. 2. If now the device be lowered directly over the rail A, it is apparent that the ends of the lugs 14, 15 and 16 will first impinge on the surface of the head of the rail, thereby permitting the weight of the device to force the edges of the jaws toward each other, and causing them to grasp the head of the rail as in Fig. 1. Simultaneously with the jaws assuming their closed position the nose of the dog 28 will engage the notch *x*. After the above it will be seen that as the cable 35 is lifted up the device will carry with it the rail A.

After the rail has been carried to the position or location desired then the operator has only to pull upon the line 36, thereby sliding the nose of the dog out of the notch which, manifestly, will release the jaws, permitting them to swing apart, and thereby releasing the rail, thus leaving the device in position for grasping another load.

In certain classes of work the cable 35 is secured to the clevis 37 in place of to the stem 5 (as is indirectly done through the ring 34 as above mentioned), in which case the nut 33 should be run down on the rod 30, thereby lifting the ear 29, and placing the dog 28 out of commission, after which the line 36 may be secured in the ring 34, in which case the jaws may be opened and closed by moving the stem 5 up and down by means of the line 36.

I desire that it be understood that various changes may be made in the several details of construction, and in the size and the relative proportions of parts, and in the substitution of other parts, without sacrificing any of the principles of this invention and without departing from the invention herein disclosed.

Having now fully shown and described my invention, what I claim and desire to secure by Letters Patent of the United States, is—

1. A device of the character described, comprising a body, a stem adapted to slide through the body, a triangular head carried on the lower end of the stem, jaws pivoted to the lower corners of the head, lugs projecting centerward from the upper end of each jaw with the lugs of one jaw alternating with the lug of the other jaw, arms extending from said body, a pin connecting said arms and extending through slots in said lugs, a clevis pivoted to the body and by which the device may be suspended, a dog carried by the body and adapted to engage in notches in the stem, and means for holding said dog out of operative position.

2. A device of the character set forth, comprising a hollow body, a stem adapted to move endwise through the body, a head carried by the lower end of the stem and below the body, a pair of jaws hinged to the lower corners of the head and adapted to move toward and from each other, lugs projecting centerward from the upper parts of said jaws, the lugs of the two jaws being adapted to lie side by side when the jaws are moved to their limit toward each other and adapted to project downwardly at convergent angles when the jaws are moved apart, an arm extending down from each side of the body, a pin connecting said arms and extending through slots in said lugs to limit the extent of movement of the jaws, means for suspending the body, and a dog for engaging the stem.
- 10 3. Rail tongs comprising a hollow body, a stem slidable in the body, a head integral with the lower end of the stem and located below said body, a pair of jaws hinged apart to the lower end of the head, a lug integral with the upper part of one of said jaws, a pair of lugs integral with the upper part of the other jaw, all of said lugs being directed inward with the lug of one jaw located be-
- 15 tween the lugs of the other jaw when the jaws are closed, means for limiting the movements of said jaws, a dog pivoted to the body and adapted to engage the stem, and means whereby the body may be suspended.
4. Rail tongs comprising a body, a stem adapted to slide in the body, a head secured to the lower end of the stem, jaws hinged to the lower corners of the head, lugs projecting inward toward each other from the upper parts of the jaws, a pin extending through slots in all of said lugs, means for supporting the ends of said pin, means pivoted to the body whereby the device may be suspended, a dog pivoted on the side of the body and adapted to project through an aperture in the side of the body to engage with notches formed in the stem, and means for holding said dog in engagement with said notches.
- 20 In testimony whereof I have hereunto subscribed my name to this specification in the presence of two subscribing witnesses.
